UNITED STATES PATENT OFFICE

2,056,641

ELECTRIC DISCHARGE TUBE

Gustav Zecher, Eindhoven, Netherlands, assignor,
by mesne assignments, to General Electric
Company, a corporation of New York

Application January 19, 1929, Serial No. 333,666
In the Netherlands March 24, 1928

7 Claims. (Cl. 250—35)

This invention relates to an electric discharge tube and particularly to an incandescent cathode electric discharge tube adapted to emit rays, preferably ultra-violet rays.

5 It is known to assist the ignition of such discharge tubes by providing one or more auxiliary electrodes.

During the operation of such discharge tubes the disadvantage may accrue that a part of the 10 tube wall which is intended for the transmission of the rays, is covered by disintegrated cathode material. Thus the transparency of the said part of the tube wall to rays is decreased and the efficiency of the discharge tube is materially 15 reduced.

According to the invention, in an incandescent cathode electric discharge tube for the emission 20 of rays, preferably of ultra-violet rays, the incandescent cathode and the part of the tube wall which is intended for the transmission of rays 25 have arranged between them one or more screens which serve at the same time as auxiliary electrodes.

Such a discharge tube may be so constructed 30 as to have extending within the discharge space a tube which may contain the substance to be irradiated one or more screens being arranged between the end of the said tube and the incandescent cathode.

35 Preferably the incandescent cathode is surrounded by a cylindrical screen.

The invention will be more clearly understood by reference to the accompanying drawing, showing some electric discharge tubes adapted to irradiate substances with ultra-violet rays.

In Figure 1 the part of the tube wall which is intended for the transmission of ultra-violet rays and which may be, for example, of quartz, is designated by 1. This quartz part 1 has sealed to 40 it glass parts 2 and 3. The stem 3 has mounted on it an incandescent cathode 4 and a screen 5 which are connected to the leading-out wires 6 and 7 or 8 respectively. The screen 5 prevents the quartz wall 1 from being struck by particles 45 disintegrated from the cathode and serve at the same time as an auxiliary electrode. The anodes 9 and 10 are arranged in the part 3 of the tube.

Referring to Figure 2, the wall 11 of the discharge tube which may be of glass for example, 50 has sealed to it a tube 12 which extends within the discharge tube 11 and which is made of a material that is transparent to ultra-violet rays, for example, of quartz. The tube 12 has sealed to it a side tube 13 and also a tube 14 which is 55 open at both ends.

The discharge tube 11 has two lateral arms 15 which have arranged in them the anodes 16 that are taken through the tube at 17.

The stem 18 of the discharge tube has mounted on it an incandescent cathode 19 to which leading-out wires 20 and 21 are connected and has moreover fixed to it a cylindrical screen 22 which protects the end of the quartz tube 12 from material particles disintegrated from the incandescent cathode 19. The screen 22 is connected to 10 the leading-out wire 23 and is thus enabled to serve at the same time as an auxiliary electrode. 5

The substance to be irradiated is admitted through the tube 14, ascends through the tube 12 and is discharged through the side tube 13. During 15 this circulation the substance may be irradiated with ultra-violet light generated in the discharge space of the tube 1.

The discharge tubes are filled with a suitable gaseous filling, for example, with a mixture of 20 argon and mercury vapour which during the discharge gives off light rich in ultra-violet rays.

What I claim is:

1. An electric discharge device for the emission 25 of ultra-violet light rays, comprising an envelope providing a discharge space and containing a cathode adapted to be heated to incandescence, an anode, an auxiliary, starting electrode, and a gaseous filling, said auxiliary electrode forming a screen located in the discharge path between 30 said anode and cathode and being arranged between said cathode and the part of the envelope wall through which the ultra-violet light rays are emitted.

2. An electric discharge device for the emission 35 of light rays, comprising an envelope providing an enclosed discharge space, and containing a cathode adapted to be heated to incandescence, an anode, an auxiliary electrode and a gaseous filling, said envelope comprising a re-entrant tube 40 adapted to contain a substance to be irradiated, said auxiliary electrode forming a screen and being arranged between said cathode and the end of said tube extending within the envelope.

3. A gas filled electric discharge device for the 45 emission of ultra-violet light rays wherein the cathode material is normally vaporized by positive ion impact thereon and deposited as an opaque coating on the envelope wall, comprising an envelope providing a discharge space and 50 containing a cathode adapted to be heated to incandescence, an anode, an auxiliary, starting electrode, and a gaseous filling, the said auxiliary electrode forming a screen for intercepting particles from said cathode and being located in the 55

- discharge path between said anode and cathode and being between said cathode and the part of the envelope wall through which the ultra-violet rays are emitted.
5. 4. An electric discharge device for the emission of light rays comprising an envelope, a filamentary cathode adapted to be heated to incandescence, an anode, and an auxiliary electrode and a gaseous filling, said envelope having a re-entrant part adapted to contain a substance to be irradiated extending therein, said auxiliary electrode forming a screen and being arranged between the said filamentary cathode and the end of said re-entrant part extending within the envelope.
10. 5. As a unitary structure, an envelope having a re-entrant tubular part for the passage of material to be irradiated, and containing a cathode adapted to be heated to incandescence, an anode, an auxiliary electrode and a gaseous filling, the said auxiliary electrode forming a screen and being mounted between said cathode and the part of the wall of the re-entrant tubular part through which the light rays are emitted.
15. 6. A unitary structure comprising an envelope comprising two concentric overlapping tubular parts sealed together and a tube opening into the

tubular part of smaller diameter of said envelope thereby defining a reverse path for material to be irradiated, the said tubular part of smaller diameter being formed of material permeable to ultra violet rays, said envelope providing a discharge space and containing a cathode adapted to be heated to incandescence, an anode, an auxiliary electrode and a gaseous filling, the said anode being mounted in a tubular portion offset with respect to and communicating with that end of the discharge space remote from the said cathode, the said auxiliary electrode forming a screen and being arranged between said cathode and the part of the wall of the tubular part of smaller diameter through which the light rays are emitted.

7. An electric discharge device for the emission of light rays, comprising an envelope providing an enclosed discharge space, and containing a cathode adapted to be heated to incandescence, an anode, a screen and a gaseous filling, said envelope comprising a re-entrant part adapted to contain a substance to be irradiated, said screen being interposed between said cathode and the re-entrant part of said envelope.

GUSTAV ZECHER.
